WRINGER ROLL CONTROL MECHANISM

Benjamin E. Getz, Morton, Ill.

Application October 31, 1934, Serial No. 750,754

14 Claims. (Cl. 68—32)

This invention has reference to a wringer roll control mechanism as applied to a washing machine, particularly of the household type.

The invention has for its principal object 5 to provide a manual control means in operative association with a wringer roll mechanism and which is responsive to the slightest touch of an operator for setting in operation a power mechanism to effect a releasing of pressure normally 10 maintaining the rolls of said wringer mechanism in frictional wringing engagement, and simultaneously interrupting the driving power connection to said wringer roll mechanism.

Other and further objects will more fully appear from the following description.

Reference is now had to the accompanying drawings illustrating a preferred embodiment of the invention, in which:

Fig. 1 is a vertical longitudinal sectional view, illustrating my invention applied to a well known form of washing machine wringer;

Fig. 2 is a vertical transverse sectional view, as the same would appear if taken on the line 2—2, Fig. 1;

Fig. 3 is a fragmentary plan, partly in section, as the same would appear if taken on the line 3—3, Fig. 1;

Fig. 4 is a fragmentary vertical longitudinal section, similar to Fig. 1, illustrating the operation of my invention;

Fig. 5 is a vertical transverse section, as the same would appear if taken on the line 5—5, Fig. 4;

Fig. 6 is a vertical transverse view, partly in section, illustrating a hand lever and connected link as the same would appear if taken on the line 6—6, Fig. 4, and

Fig. 7 is a view similar to Fig. 6 illustrating the members in disconnected relation.

Like characters of reference denote corresponding parts throughout the figures.

Reference now being had to the drawings, 1 designates a wringer frame in which is operatively received the usual wringer rolls 2 and 3, the inner end of said frame being suitably connected to a gear housing 4. Said housing is supported by a depending tubular post 5, the lower end of which comprises an enlarged base 6 which is seated upon a head portion 7 of a stationary tubular post 8. The post 8, although not so shown, may be suitably connected to a washing machine tub or frame of a machine or may constitute in the lower extension thereof of a leg of a machine, as is done in many cases. 55 The base 6 is shown having a depending periph-

eral flange 9 overlapping the peripheral vertical side face 10 of the head portion or seat 7. A plurality of notches 11 are provided in said side face 10 of the head portion 7 to receive the latching end 12 of a manually operated hand 5 lever 13 pivotally mounted on the base 6 at 14. The main body portion of said lever is bifurcated at 16 to provide a U-shaped member which embraces the post 5, the oppositely disposed portions of said U-shaped member providing hand 10 hold operating members 16. A coiled spring 17 normally urges the latching end 12 of the lever 13 within the locking notches 11 of the head portion 7.

It will be understood that the wringer frame 15 and rolls designated 1, 2 and 3, including the gear housing 4 and post 5 may be adjusted radially upon the head portion 7 of the post 8 in any desired position and locked in such positions through the medium of the lever 13 with its 20 latching end 12 in the notches 11. In other words, the wringer and housing are of the conventional swinging type, well known in the art.

A main drive shaft 18 is operatively disposed within the posts 5 and 8, and while not shown, it will be understood that it may be driven by either an electric or gasoline motor or other suitable power means. The upper end of said shaft is preferably keyed to a horizontally disposed driving pinion 19 which has constantly 25 meshing engagement with oppositely disposed gears 20 and 21 which are loosely mounted upon a horizontally disposed drive shaft 22, the ends of said shaft being journaled in bearings 23 and 24 of said housing 4. 30

Means for optionally clutching the gears 20 and 21 to produce rotation of the shaft 22 in one direction or the reverse is provided in the male clutch member 25 slidably keyed upon the shaft 22. On opposite side faces of said member 25 are male clutch portions 26 which are adapted to engage the female clutch portions 27 of the gear 20, and 28 of the gear 21. The means for accomplishing the moving of the male clutch member 25 upon the shaft 22 into 45 operative engagement with the gears 20 and 21 is provided in a crank member 29 which forms a depending part of a manually operated lever arm 30 disposed exteriorly of the gear housing 4, said crank member 29 operating within the 50 groove portion 31 of said clutch member 25.

Assuming the drive shaft 18 being rotated, in Fig. 1 the lever 30 is illustrated in neutral position, that is, by reason of the position of the clutch member upon the shaft 22 being out of en- 55

gagement with either of the gears 20 and 21, no rotation of said shaft 22 will be effected. In Fig. 4 the lever arm 30 is illustrated in an operative position resulting in the clutching of the member 25 with the gear 21, thereby imparting rotation in one direction to the driving shaft 22. In order to reverse the rotation of the driving shaft 22, it will be apparent that it is only necessary to reverse the position of the lever arm 30 from the position shown in Fig. 4, such reversed position of the arm causing the clutch member 25 to have clutching engagement with the gear 20 resulting in imparting a reverse rotation to the driving shaft 22.

Disposed adjacent the bearing 24 is a gear 32, preferably keyed to the shaft 22 which is adapted to have a constant meshing engagement with an idler gear 33 loosely mounted upon a preferably fixed shaft 34, see Figs. 1, 2, and 4.

Referring now particularly to Fig. 1, the wringer rolls 2 and 3 are illustrated therein in tensioned frictional engagement ready for a wringing operation. The lower wringer roll 2 is fashioned upon a suitable shaft 2^a, the end portions of which are received within bearing blocks 35 which are adapted to be normally seated upon block rests 36 in said frame 1. On each of the lower portions of said blocks 35 are depending stub members 37 which cooperate with similar upstanding stub members 38 provided on the base of the frame 1 by means of interposed coil springs 39 which normally urge the bearing blocks 35 upwardly away from their supports 36 and thus displace the wringer roll 2 from the position shown in Fig. 1 to the inoperative position shown in Fig. 4, the accomplishment of which is to be described. The inner end of the wringer roll shaft 2^a is extended somewhat beyond the limits of its bearing block 35 and has preferably keyed to the end thereof a gear 40, preferably alike in all respects to the gear 32, and adapted to have a normal meshing engagement with the idler gear 33, whereby, as illustrated in Fig. 1, it will be apparent that upon the proper positioning of the hand lever 30 to give rotation to the shaft 22, such rotation will be transmitted to the gear 32, to the idler gear 33 and thence to the gear 40 and thus revolve the lower driving wringer roll 2 which will normally rotate its associated wringer roll 3 by reason of frictional tensioned engagement therewith.

The upper wringer roll 3 is similarly fashioned upon a suitable shaft 3^a, the end portions of which are similarly received within bearing blocks 41. Each of the blocks 41, preferably at their base portions, are provided with laterally oppositely disposed projections 42, in which each is provided with an opening 43 adapted to receive an elongated spring supporting rod 44, the lower end portion of which is threaded to receive adjusting nuts 45. The upper ends of said rods 44 are received within openings 46 in similar laterally oppositely disposed projections 47 of saddle blocks 48, the upper end portion of said rods being likewise threaded to receive preferably lock nuts 49. On each of the rods 44 there is provided a coiled spring 50 disposed between the pairs of end blocks 41 and 48.

A head wringer frame member 51 is adapted to overlie the top of the wringer frame 1 and have detachable connection therewith. Provided in the interior length of said member is a manually adjustable shaft 52 suitably journaled at the ends thereof. Eccentric members 53 are suitably secured to said shaft to have bearing en-

gagement with circular recesses 54, one each provided in the top portion of said saddle blocks 48. A manual lever 55 is preferably secured exteriorly of the frame member 51 to the inner end of said shaft 52, whereby the eccentrics 53 may be rotated within the recesses 54 of said saddle blocks 48.

At each inner end of the shaft 52 are loosely connected depending links 56, the lower end length portions of which are provided with slot openings 57. At each inner upper end of the wringer frame 1 is provided a link retainer member 58 upon which the links 56 may have movement the length of the slot openings therein. In other words, upon the releasing of the head frame member 51 from securement with the wringer frame 1, said member may be removed away from said frame in a substantially upward direction a distance equal the length of the slot openings 57, as illustrated in Fig. 4. The links 56 function further to prevent the complete separation of the frame member 51 with its wringer frame 1, as will be understood. At the outer upper end of the wringer frame 1, see Fig. 1, is provided a catch member 59 adapted to cooperate in latching manner with a catch member 60 provided on the depending portion of the head frame member 51 which serves to adequately lock that end of the members 1 and 51 and permit their quick detachment when the member 51 is released.

The locking and releasing of the head frame member 51 with the wringer frame 1 is accomplished by the following mechanism. The inner hub portion of the lever 55 is provided with a circular groove or channel 61 communicating with the periphery of the hub portion at openings 62 and 63, best seen in Figs. 6 and 7. In Figs. 1, 4 and 6, a roller-like lug 64 forming a part of a latching plate 65 is shown disposed within the groove or channel 61. The upper end of said plate is adapted to be operatively disposed between the hub portion of said lever 55 and the end portion of said head frame member 51 and is provided with a U-shaped opening 66 to embrace the outer extension of the shaft 52. The lower end of said plate 65 is preferably tapered as at 67 to facilitate the entrance and withdrawal thereof in the opening 68 in said wringer frame 1. In the normally seated and latched position of said latching plate 65, the lower end of said plate rests upon a wringer frame ledge member 69, as shown in Fig. 1. Said tapered end portion of the plate 65 is provided with an opening 70 adapted to receive the acting end 71 of a manually actuated latching rod 72, said plate and rod shown in latched or locked position in Fig. 1 and in unlatched or released position in Fig. 4. The latching rod 72 is adapted to have a limited longitudinal slideable and reciprocal powered movement between the wall of the housing 4 and the supporting members 73 and 74, the inner end of said rod being received within a recess 75 in which is located a small coiled spring 76 which normally urges the leg 77 of the rod 72 in abutting relation with a depending wall of the housing 4, such position of the leg 77 illustrated in Fig. 1.

Provided in an enlarged depending portion 78 of the latching rod 72 is a vertical opening in which is adapted to be operatively disposed a push pin 79, the upper portion of which extends outwardly of an opening 80 in the gear housing 4. A coiled spring 81 is disposed about 75

the upper portion of said pin and is seated upon the upper surface of said rod 72 and a manually operable member 82 is suitably secured upon said upper end of the pin 78, the lower base portion of said member 82 being rested upon said coiled spring, as shown in Figs. 1 and 4. The function of the coiled spring 81 is to normally support the pin 78 in an inoperative position with respect to the gear member 20 therebelow, the acting end of said pin 78 being normally preferably flush with the end opening of said depending portion 78, see Fig. 1.

The gear 20 in addition to the gear portion which meshes with the gear 19 is provided with a circular groove 83 having one or more cam portions therein as at 84 in which is adapted to be received and actuated the end portion of the pin 78, as illustrated in Fig. 4.

Referring to Figs. 1, 3, 4 and 5, there is illustrated a supplemental manually operable element connected with the manually operable member 82 comprising rods 85 slidably and pivotally mounted at opposite sides of the outer end of the wringer frame 1 at 86. Said rods 85 preferably embrace the length of the wringer frame in close proximity to the wringer rolls 2 and 3, as shown. At the inner end of said wringer frame 1 said rods are shown bent inwardly and slightly downwardly and connected by suitable means, such as screws 87 to a yoke-like member 88 which has a suitable fitting relation with the member 82 and pin 78.

From the foregoing description, it will be apparent that to cause the pin 78 to become operatively associated with the groove 83 of the gear 20 requires only the slightest touch of an operator upon the manually operable member 82 in a downward direction; also, should it be inconvenient for an operator to reach the remote control means 82, it will be apparent that the operator has only to apply to either of the rods 85 the slightest touch in a downward direction resulting in the member 82 and pin 78 being simultaneously actuated and the pin 78 brought into operative contact with the groove 83 and cams 84 thereof of the gear 20.

In Fig. 1 the wringer mechanism is illustrated ready for a wringing operation, the wringer rolls 2 and 3 being frictionally engaged and held in tensioned relation for the proper wringing of clothes and fabrics. Assuming the source of power is rotating the drive shaft 18, it will be apparent from Fig. 1 that the gear 19 will be imparting rotation to the gears 20 and 21 but on account of the neutral position of the hand lever 30 no rotation will be imparted to the shaft 22.

Assuming the hand lever 30 is moved to the position shown in Fig. 4, it will be seen that the gear 21 by reason of the clutch connection with the clutch member 25 will impart rotation in one direction to the drive shaft 22, said shaft similarly rotating the gear 32 which imparts rotation to the idler gear 33 which transmits its rotation to the wringer roll gear 40 and revolves the lower wringer roll shaft 2^a and roll 2 thereon, said lower roll 2 rotating the upper wringer roll 3 by frictional engagement therewith, as is customary.

It will be apparent that upon the shifting of the hand lever 30 to an opposite position from that shown in Fig. 4, the shifter clutch member 25 will be clutched with the gear 20 resulting in the rotation of the shaft 22, gears 32, 33 and 40, and wringer shafts 2^a, 3^a and

wringer rolls 2 and 3 thereon in an opposite direction.

Should it be desirable to suddenly release the pressure between the operating wringer rolls 2 and 3, regardless of their direction of rotation, the operator has only to apply the slightest downward touch to either the rods 85 or directly upon the member 82, which momentarily results in the downward movement of the pin 78 into operative engagement with the groove 83 forming a part of the fast rotating gear 20. The rotating cam portions 84 cause the pin 78 and the rod 72 to be momentarily reciprocated longitudinally compressing the coiled spring 81 and simultaneously breaking the latching connection between the members 85 and 71, that is, the acting end 71 of the latching rod 72 is withdrawn from the opening 70 in the latching plate 66 releasing said plate, see Fig. 4. The manual actuation of either the rods 85 or the hand member 82, to cause the pin 78 to be displaced as above described, it will be understood, requires only the slightest touch on the part of the operator, whereupon, the coiled spring 81 lifts the pin 78 immediately out of contact with the groove 83 to its normal inoperative position, as shown in Fig. 1.

Immediately following the power unlatching of the members 71 and 85, the compressed coiled springs 80, associated with the upper wringer roll 3, become free to force upwardly their saddle blocks 48 which bear against the eccentrics 53 and bodily raise the head frame member 51 from connection with the wringer frame 1 to substantially the position shown in Figs. 4 and 5. Such so-called freeing of the upper wringer roll 3 from its driven association with the lower roll 2 simultaneously results in the compressed coil springs 88 bodily raising the bearing blocks 36 and associated wringer roll 2 to the approximate position illustrated in Figs. 4 and 5, such raising of the lower roll 2 and its shaft 2^a causing the wringer drive gear 40 to be lifted out of mesh with its driving idler gear 33, thereby disconnecting the driving power to said wringer roll mechanism.

The merits of such a wringer roll control mechanism are quite obvious. In a wringing operation, should there occur a hard tangling of the clothes or fabrics to warrant a quick release of the pressure between the wringer rolls, or should a part of the clothing of the operator or a member of the body, such as a hand, become accidentally drawn between the operating wringer rolls, it will be apparent that only a slight touch of either the rods 85 or the member 82 by the operator will be required to set into motion power means for immediately releasing the pressure between the wringer rolls 2 and 3, thereby displacing the rolls from each other, and also, simultaneously disconnecting the driving power to the lower roll 2, thus eliminating to the greatest degree the possibility of damage either to the articles being wrung or to accidentally lodged members of the body.

It will be understood from a study of Fig. 4 that the relative released position of the upper wringer roll 3 is that position assumed when clothes or fabrics are still disposed between the separated rolls. Upon withdrawing the clothes or fabrics from between the separated rolls, the upper roll 3 would fall against the released lower roll 2, however, such weight would not be sufficient to cause the wringer

gear 40 to become enmeshed with the driving idler gear 33.

To reassemble the pressure released and stopped wringer rolls 2 and 3 to the normal wringing position illustrated in Fig. 1, the operator first moves the hand lever 30 to the neutral position shown in Fig. 1 to stop the rotation of the driving shaft 22 and its connected rotative elements previously referred to, it being understood that the power driven main drive shaft 18 may continue to run, including the gears 20 and 21, if desired.

The operator next latches the connecting members 59 and 60 located at the outer end of the head frame member 51 and the wringer frame 1, as shown in Fig. 1, and following the lowered movement of the head frame member 51, the lever 55 is preferably moved from the locked position shown in Figs. 1, 4 and 6 to the plate releasing position illustrated in Fig. 7, such movement of the lever 55 incidentally rotating the eccentrics 53 on the shaft 52 to a position substantially opposite that shown in Fig. 5; also, such movement of the lever releases the engagement of the roller like lug 64 within the circular groove 66, whereupon the tapered end 67 of said plate is guided into the recessed opening 68 in the frame 1. At this point, the latching end 71 of the rod 72 may be removed away from the opening 68 to permit the free downward passage of the end of the plate 65 in normal seated engagement upon the ledge 69 in different manner. Should it be that the main drive shaft 18 is rotating and with it the gear 20, a similar slight downward touch of the rods 85 or the member 82 will cause the pin 79 to enter the groove 83 and be momentarily reciprocated by one of the cam portions 84, thereby unobstructing the opening 68 and permitting the downward passage of the latching end of the plate 65 followed by the latching end 71 of the rod 72 entering the opening 70 in said plate 65 in locking relation therewith, in the manner shown in Fig. 1. With the power disconnected from the main driving shaft 18, as might be the case, this same operation may be accomplished by momentarily manually reciprocating the rod 72 by moving either the rods 85 or the member 82 longitudinally, compressing the coiled spring 76 and thereby displacing the latching end 71 to permit the downward passage of the latching end of the plate 65. In the manual longitudinal operation of displacing the rod 72, the pin 79 need not be caused to be pressed downwardly since with the gear 20 stationary, no resultant power reciprocal action of the rod 72 would follow.

In the reassembling steps so far described, it will be understood that the lowering and partial locking of the head frame member 51 upon the wringer frame 1 restores the wringer rolls 2 and 3 in a slight tensioned relation, since the springs 39 in the lowering of the lower roll 2 become compressed in the remeshing of the wringer roll gear 40 with the now stationary idler gear 33. The final pressing downward of the inner end of the head frame member 51 with the hand lever 55 in the position shown in Fig. 7 permits the entrance of the roller-like lug 64 into preferably the opening 62 of the channel or groove 61, whereupon the operator moves the lever 55 to substantially the position illustrated in Fig. 6 which results in the eccentrics 53 bearing downwardly upon the saddle blocks 48 and compressing the coiled springs 50 and simultaneously compressing the upper wringer roll 3 upon the lower

wringer roll 2 in tensioned frictional engagement therewith, ready for a wringing operation as shown in Fig. 1.

What I claim is:

1. The combination with separable cooperatively related rolls, a frame, means for yieldably pressing them together in said frame, including a manual control, power means for effecting rotation of the rolls when under pressure including a connection adapted to be broken between the source of power and the rolls, and means supplemental to said manual control including an actuator operable under relatively light pressure compared to that required to operate the manual control and to operate a member arranged to be engaged with a member on the power means so that said supplemental means will effect release and separation of the rolls and enable breakage of said connection to stop the rotation of the rolls under power and leave both of them free to turn independently of the power means.

2. The combination with separable cooperatively related rolls, a frame, means for yieldably pressing them together in said frame including a manual control, power means for effecting rotation of the rolls when under pressure including interruptable gearing between the power means and the rolls, and means supplemental to said manual control including an actuator operable under relatively light pressure compared to that required to operate the manual control and to operate a member arranged to be engaged with a member on the power means so that said supplemental means will effect release and separation of the rolls and enable disconnection of said interruptable gearing to stop the rotation of the rolls under power and leave both of them free to turn independently of the power means.

3. In a wringer, separable cooperatively related rolls, a frame therefor, manually operable means for effecting the desired normal pressure between the rolls, power driving means for the rolls, and emergency releasing instrumentalities including a sensitive manual control for initiating the release operation, and means operatively associated therewith to cause the power to release and thereby permit separation of the rolls and enable freeing the rolls from the driving means whereby they are both free for rotation independently of the driving means.

4. In a wringer, a pair of separable cooperatively related rolls, a frame therefor, power means for driving the same, manually operative means for creating the desired normal pressure between the rolls, a releasable latch member detachably connected at one end with said manual means, and a releasable latch member associated with the other end thereof operatively associated with the power means whereby to be released by said power means.

5. In a wringer, a pair of separable cooperatively related rolls, a frame therefor, power means for driving the same, manually operative means for creating the desired normal pressure between the rolls, a releasable latch member carried at one end by said manual means, and a driving-power releasable latch member associated with the other end thereof.

6. In a wringer, a pair of separable cooperatively related rolls, a frame therefor, power means for driving the same, manually operative means for creating the desired normal pressure between the rolls including a hand-control, a shaft operated thereby, and camming means

- thereon, a link carried at one end by said hand-control, and a releasable latch on said frame and cooperatively related to the other end of said link.
5. In a wringer, a pair of separable cooperatively related rolls, a frame therefor, power means for driving the same, manually operative means for creating the desired normal pressure between the rolls including a hand-control, a shaft operated thereby, and camming means thereon, a latch connection carried by said hand-control, a releasable latch on said frame and cooperatively related to said connection, and a sensitive manually controlled power means for releasing the latch.
10. In a wringer, a pair of separable cooperatively related rolls, a frame therefor, power means for driving the same, manually operative means for creating the desired normal pressure between the rolls including a hand-control, a shaft operated thereby, and camming means thereon, a latch connection separably carried by said hand-control, a releasable latch on said frame and cooperatively related to said connection, and a sensitive manually controlled power means for releasing the latch.
15. A pair of separable cooperatively related rolls, a frame therefor, manually operable means for creating the desired normal pressure between the rolls, a power drive for the rolls, latching means for maintaining the rolls in driving relationship, and means for releasing the latch comprising a sensitive control member, and a rotating cam member on the power drive cooperating therewith to release the latch.
20. In a wringer, a pair of separable cooperatively related rolls, a frame therefor, manually controllable means for creating the desired normal pressure between the rolls, a power drive for the rolls including a driven gear on one of them, a driving gear in axial relationship thereto, and a common gear meshing with both of said driving and driven gears to impart motion from one to the other, latching mechanism adapted on its release to permit separation of the rolls and separation of the gearing including a member movable in a path parallel to the axis of the driving and driven
25. gears, a sensitive manual actuating member for the latch including a cooperating part to effect release of the latch by power.
11. In a wringer, a pair of separable cooperatively related rolls, a frame therefor, manual means for creating the desired pressure therebetween, a power drive for said rolls including a driving gear and shaft therefor, a latch for retaining the rolls in normal relationship having a part movable in a plane parallel to the 10 axis of said shaft, a sensitive control member for the latch, and a member mounted to rotate with said shaft to cooperate with said control in effecting release of the latch by power.
12. In a wringer, a pair of separable cooperatively related rolls, a frame therefor, manual means for creating the desired normal pressure therebetween, a power drive for the rolls, and a release mechanism including a latch, a sensitive control member for the latch mounted in 20 adjacency to the rolls, a pin adapted to be depressed by the latter, and a cam moving with the drive cooperating with said pin to release the latch by power.
13. In a wringer, a pair of separable cooperatively related rolls, a frame therefor, manual means for creating the desired normal pressure therebetween, a power drive for the rolls, and a release mechanism including a latch, a sensitive control member for the latch mounted in 25 adjacency to the rolls, a pin adapted to be depressed by the latter, and a cam moving with the drive cooperating with said pin to release the latch by power, in combination with an auxiliary manually engageable means for depressing said pin in lieu of operating said first mentioned sensitive means.
14. In a wringer, a pair of separable cooperatively related rolls, a frame therefor, power means for driving the same, manually operative 40 means for creating the desired normal pressure between the rolls, a latch member carried at one end by said manual means, and a releasable latch member associated with the other end thereof operatively associated with the 45 power means whereby to be released by said power means.

BENJAMIN E. GETZ.
